DRYING METHOD AND APPARATUS FOR
CYLINDRICAL ARTICLESWesley L. Webb, Glen Moore, Pa., assignor to
American Viscose Corporation, Wilmington,
Del., a corporation of Delaware

Application June 30, 1944, Serial No. 542,857

13 Claims. (Cl. 34—21)

1

This invention relates to methods and apparatus for drying hollow articles, such as cylindrical articles having a perforated end surface, and it is of a special advantage for drying spinnerets, such as are used in the production of artificial filaments.

In accordance with the present invention, the articles are passed along a path and a fluid medium is directed against the article from two different directions, that from one direction entering the hollow article and that from the other direction being blown across the end of the article, and the article is rotated as it passes through the path. Additional objects, features and advantages of the invention will be apparent from the drawing and the description thereof hereinafter.

In the drawing, illustrative of the invention,

Figure 1 is a plan view of a form of apparatus adapted to dry spinnerets in accordance with the invention,

Figure 2 is an elevation of the apparatus of Figure 1, and

Figure 3 is a cross-section taken on line III—III of Figure 1.

Referring to the drawing, a panel or table 2 carries a wall 3 and a guide strip 4. Rotatably mounted at each end of the table are pulleys 5 and 6 respectively, the former being adapted to be driven by a shaft 7 carrying the gear 8 while the latter pulley 6 is mounted on a shaft 9 slidable within the slot 10 in the panel 2. The shaft 9 is carried in the yoke 11 which extends through the opening 12 in the panel. A rod 13 reciprocable within the projection 14 upon the panel 2 is secured at one end to the yoke 11 and has a head 15 at the other end against which a spring 16 presses, thereby tensioning the belt 17 carried by the pulleys 5 and 6.

The belt 17 is arranged so that one of its courses passes along the surface of the wall 3 opposite the guide 4 at a small distance above the top surface of the panel so that the flange 18 of the spinneret 19 does not interfere with the making of contact between the belt and the spinneret surface. The wall 3 may be undercut at 20 to accommodate articles having larger flanges. Similarly, the guide 4 is spaced somewhat above the top surface of the panel to accommodate the flange 18 of the spinneret. As shown, this is accomplished by provision of a shim 21 below the guide 4.

A fluid supply duct 22 is secured to the under surface of the panel and communicates with two slots 23 and 24 respectively disposed in the panel on opposite sides of the wall 3 so that slot 23

directs the fluid upwardly into the spinneret passing thereover and slot 24 directs the fluid upwardly into a housing 25 which is enclosed at both ends and communicates only with the slot 26 in wall 3. Slot 26 is disposed sufficiently high in the wall 3 that the fluid is directed above the belt 17 and across the end surface of the spinneret or other article being passed therethrough. A conduit 27 may serve to supply air to the duct 22. A hood 28 is secured to the wall 3 so that it encloses the article passage way except for the necessary opening to permit entrance and exit of the articles with respect thereto. The upper portion of the ends may be partially enclosed by the walls 29.

A fluid discharge slot 30 may be provided along side the slot 23 but spaced from it so that it does not communicate with the supply duct 22. This discharge slot serves to permit the discharge of fluid and any liquid or vapor spray from both the inside as well as the outside of the articles.

An entrance guideway is shown comprising the strips 31 and 32 respectively and an exit guideway is divided between the strips 33 and 34 respectively, all of such strips being undercut as shown at 35 or provided with shims in a manner similar to the guide 4 to permit free passage of the flange of any article being handled.

In operation, the spinnerets or the articles pass in the direction indicated by the arrow through a path comprising the entrance guideway, the passage over the slots 23 and 30, and exit between the guides 33 and 34. The articles may be fed to the entrance guideway between strips 31 and 32 by hand or the device may be disposed so that it slopes downwardly in the direction of the belt so that the articles are fed by gravity to the belt. In this event, the entrance guideway may be made considerably larger so that it is adapted to be charged with a considerably greater number of spinnerets. Regardless of the way in which the spinnerets or articles are caused to come into contact with the belt 17, the belt propels them along their path through the chamber 28 and in doing so causes them to rotate about the tangent they make against the guide 4. The action of the belt against accumulated articles or spinnerets causes them to be forced through the exit guideway and thence to a container not shown. A blast of fluid is directed into the hollow article as it passes over the slot 23 and the action of the blast of fluid through the slot is most vigorous on the strips of the inside circumferential surface of the spinnerets which are in alignment directly with the slot 23. However, since the

article is rotated as it travels through its path, the fluid blast exerts vigorous action at successive overlapping longitudinal strips of the inside circumferential surface of the spinneret. As the blast of fluid strikes the end wall of the article, it is deflected in a turbulent fashion to sweep over the inside surface and where that surface is perforated as in a spinneret, a portion of the blast passes directly through the perforations, particularly those which are directly in alignment above slot 23. Again, because of the rotation of the article, the most vigorous passage of the fluid blast through the perforations is effected through those immediately above the slot 23 at any given moment but eventually through all of the perforations as they are presented successively in alignment above the slot.

The blast of fluid passing through slot 26 exerts a vigorous action across the face of the article and where there are perforations through the end thereof as in the case of spinnerets, the direction of the blast from slot 26 at an angle transverse to the direction that would be taken by the fluid blast passing through the perforations from the inside of the article serves to assist in cleaning the outer surface and of simultaneously improving the effect of the fluid streams passing through the perforations instead of reducing their effect by opposing their force. The air blast after passing over the end of the article is deflected downwardly to sweep over the outer surfaces thereof and is finally discharged through the slot 30 where it is not covered by the article. Rotation of the articles as they pass along their path serves to bring fresh portions of the end surface as well as of the circumferential surface of the articles successively into the most effective disposition with respect to the fluid trend in chamber 28 so that as in the case of the inside surfaces, the outer surfaces as well are cleaned or dried in an efficient and economical manner.

The system of the present invention may be applied to the drying of hollow articles having one end closed, such as cans, though as pointed out hereinabove, it finds its most advantageous use in connection with the drying and cleaning of articles having one end perforated such as spinnerets. The method and apparatus may be performed and operated with any fluid desired, such as cold or hot air for drying; or steam, hydrocarbon or chlorinated solvents, for cleaning, steam being useful for simultaneously cleaning and drying. The articles may have a flange at one or both ends or none at all. As shown, the flange 18 of the spinneret 19 serves to maintain the spinneret in position during treatment.

It is to be understood that the description herein is illustrative only and that variations and deviations may be made without departing from the spirit of the invention as defined in the appended claims.

I claim:

1. The method of treating hollow cylindrical articles having one end surface, said surface being perforated, comprising the steps of passing the article through a path, continuously directing a fluid blast into the interior of the article as it passes through a longitudinal zone of the path, continuously directing a fluid blast first across the outside end surface and then generally axially about the cylindrical surface as it passes through the zone and rotating the article as it passes through the zone to present a fresh portion

of the interior and exterior surfaces to the most vigorous part of the blast.

2. The method of treating hollow cylindrical articles having one end surface substantially at right angles to the axis, said surface being perforated, comprising the steps of passing the article through a path, continuously directing a fluid blast into the interior of the article as it passes through a longitudinal zone of the path, continuously directing a fluid blast first in a direction approximately at right angles to that of the first blast across the outside end surface and then generally axially about the cylindrical surface as it passes through the zone, and rotating the article as it passes through the zone to present a fresh portion of the interior and exterior surfaces to the most vigorous part of the blast.

3. The method of treating hollow cylindrical articles having one end surface, said surface being perforated, comprising the steps of passing the article through a path, continuously directing a fluid blast into the interior of the article adjacent one side of its axis as it passes through a longitudinal zone of the path, continuously directing a fluid blast first across the outside end surface and then generally axially about the cylindrical surface as it passes through the zone, continuously discharging the fluid from both the interior and the exterior of the article adjacent the other side of its axis as it passes through the zone, and rotating the article as it passes through the zone to present a fresh portion of the interior and exterior surfaces to the most vigorous part of the blast.

4. The method of treating hollow cylindrical articles having one end surface substantially at right angles to the axis, said surface being perforated, comprising the steps of passing the article through a path, continuously directing a fluid blast into the interior of the article adjacent one side of its axis as it passes through a longitudinal zone of the path, continuously directing a fluid blast first in a direction approximately at right angles to that of the first blast across the outside end surface and then generally axially about the cylindrical surface as it passes through the zone, continuously discharging the fluid from both the interior and the exterior of the article adjacent the other side of its axis as it passes through the zone, and rotating the article as it passes through the zone to present a fresh portion of the interior and exterior surfaces to the most vigorous part of the blast.

5. Apparatus for treating hollow cylindrical articles with fluids comprising a guide, belt means engaging the external cylindrical surface of the articles for rolling the articles in contact with the guide through a path therealong, means extending a substantial distance alongside the path of the articles along the guide for directing a blast of fluid into the articles and additional means for directing a blast of fluid across and substantially parallel to the face of the articles.

6. Apparatus for treating hollow cylindrical articles with fluids comprising a guide, belt means engaging the external cylindrical surface of the articles for rolling the articles in contact with the guide through a path therealong, means extending a substantial distance alongside the path of the articles along the guide for directing a blast of fluid into the articles, additional means for directing a blast of fluid across and substantially parallel to the face of the articles, and a housing enclosing at least that portion of

the path of the articles adjacent the fluid blast means, said housing having entrance and exit openings at the ends thereof.

7. Apparatus for treating hollow cylindrical articles with fluids comprising a guide, belt means engaging the external cylindrical surface of the articles for rolling the articles in contact with the guide through a path therealong, means extending a substantial distance alongside the path of the articles along the guide for directing a blast of fluid into the articles, additional means for directing a blast of fluid approximately at right angles to that of the first fluid blast across the face of the articles.

8. Apparatus for treating hollow cylindrical articles with fluids comprising a panel, a guide on the panel, an endless belt having one course spaced from the guide to form a passageway for the articles therebetween, means for continuously driving the belt to roll the articles through the passageway, a slot in the panel alongside the passageway, fluid supply means communicating with said slot, and means spaced from the panel and opening into the passageway for directing a blast of fluid thereinto in a direction transversely of that of the fluid entering through the slot.

9. Apparatus for treating hollow cylindrical articles with fluids comprising a panel, a guide on the panel, an endless belt having one course spaced from the guide to form a passageway for the articles therebetween, means for continuously driving the belt to roll the articles through the passageway, a slot in the panel alongside the passageway, fluid supply means communicating with said slot, and means opening adjacent the side of the belt away from the panel for directing a blast of fluid into the passageway.

10. Apparatus for treating hollow cylindrical articles with fluids comprising a panel, a guide on the panel, an endless belt having one course spaced from the guide to form a passageway for the articles therebetween, means for continuously driving the belt to roll the articles through the passageway, a housing on the panel for enclosing the passageway, entrance and exit openings at the ends of the housing, a slot in the panel alongside the passageway, fluid supply means communicating with said slot, and means opening into the housing adjacent the side of the belt away from the panel for directing a blast of fluid into the passageway.

11. Apparatus for treating hollow cylindrical articles with fluids comprising a panel, a guide on the panel, an endless belt having one course spaced from the guide to form a passageway for the articles therebetween, means for continuously driving the belt to roll the articles through the passageway, a housing on the panel for enclosing the passageway, entrance and exit openings at

the ends of the housing, a slot in the panel alongside the passageway, fluid supply means communicating with said slot, means opening into the housing adjacent the side of the belt away from the panel for directing a blast of fluid into the passageway, and a second slot in the panel alongside the passageway for discharging fluid therefrom.

12. Apparatus for treating hollow cylindrical articles with fluids comprising a panel, a guide on the panel, an endless belt having one course spaced from the guide to form a passageway for the articles therebetween, means for continuously driving the belt to roll the articles through the passageway, a housing on the panel for enclosing the passageway, entrance and exit openings at the ends of the housing, a slot in the panel alongside the passageway, fluid supply means communicating with said slot, means opening into the housing adjacent the side of the belt away from the panel for directing a blast of fluid into the passageway, and a second slot in the panel alongside the passageway for discharging fluid therefrom, said second slot being disposed alongside the first slot on the side thereof away from the blast directing means adjacent the other side of the belt.

13. Apparatus for treating hollow cylindrical articles with fluids comprising a panel, a guide on the panel, an endless belt having one course spaced from the guide to form a passageway for the articles therebetween, means for continuously driving the belt to roll the articles through the passageway, a housing on the panel comprising a wall against a portion of which the belt rides for enclosing the passageway, entrance and exit openings at the ends of the housing, a slot in the panel alongside the passageway, a slot in the wall adjacent the side of the belt away from the panel, fluid supply means communicating with said slots, another slot in the panel alongside the first slot therein spaced to the side thereof away from the wall for discharging fluid from the passageway.
